DISK ROLLING MACHINE

Leslie H. Goodell, St. Francis, Kans., and Leverett Ercil Goodell, Haigler, Nebr.

Application August 11, 1952, Serial No. 303,806

4 Claims. (Cl. 153—54)

1

This invention relates to a disc rolling device. Discs of the type used on disc plows and cultivators often become damaged from striking rocks and other obstructions. The damage usually consists of distorting the normal plane of the discs so that they will not freely roll and turn the soil. The principal object of this invention is to provide a device which will quickly roll a deformed disc back to its perfect normal condition.

Disc rolling devices have been used for this purpose, but these devices require that either the discs or the disc shafts be completely removed from the implement and carried to and from the disc rolling device. Another object of this invention is to provide a relatively light, portable, adjustable disc rolling device which will roll and re-form the discs of any type while the latter are in place upon the implement, so as to save the valuable time usually lost in removing and replacing the discs and transporting them to and from a rolling device.

Certain types of discs are formed with a substantially semi-spherical contour, and the usual disc rolling device operates only on the peripheral edge and is unable to follow the arcuate, spherical contour of the disc. A further object of this invention is to provide a portable disc rolling device which will automatically follow the original arcuate contour or "dish" of the disc to bring deformed discs back to their original state.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved disc rolling device, illustrating it in relation to a disc shaft and discs of a conventional farm implement;

Fig. 2 is a rear view of the device;

Fig. 3 is a horizontal cross-section, taken on the line 3—3, Fig. 2;

Fig. 4 is a similar cross-section, taken on the line 4—4, Fig. 2;

Fig. 5 is a similar cross-section, taken on the line 5—5, Fig. 2; and

2

Fig. 6 is a vertical section, taken on the line 6—6, Fig. 2.

The improved disc rolling device is supported on a track frame consisting of two parallel, V-shaped track members 10 fixedly connected at their extremities by means of cross frame members 11 welded or otherwise secured to the track members 10.

The device is mounted on a supporting base plate 12. One side of the base plate 12 is slidably supported from one of the track members 10 on a V-shaped runner 13 welded to the bottom of the plate 12. The other side of the base plate 12 is welded or fixedly mounted on a sliding sleeve 14 which is arranged to travel along a slide rod 15 welded at its extremities to the cross frame members 11 and positioned in the second track member 10.

The disc rolling portion of the device is supported on a hollow pedestal 16, the bottom of which is closed by means of a bottom plate 17 which projects to one side of the pedestal 16 to form a clamping shelf 18. The shelf 18 extends beneath a hold-down strap 19 welded at its extremities to the base plate 12 and overlying the shelf 18. A set screw 20 is threaded through the strap 19 and engages the shelf 18 to lock the latter in any desired position.

The pedestal 16 is eccentrically pivoted on a pivot bolt 21 extending through an angle clip 22 welded or otherwise secured on the pedestal 16. It can be seen that by loosening the set screw 20, the pedestal 16 may be swung in an arc about the axis of the bolt 21.

The top of the pedestal 16 is partially closed by two sector-shaped, spaced apart top plates 23, the adjacent edges of which are reinforced by means of two parallel guide angles 24.

A box-like bearing housing 25 rests upon the top plates 23. A square, tubular post 26 extends downwardly from the bearing housing 25 between the angle guides 24 and terminates in a threaded nut 27 which is welded or otherwise secured on a square plug 28 fitted into the square post 26.

The nut 27 is threaded onto a horizontal jack shaft 29, which terminates exteriorly of the pedestal 16 in a hand wheel 30. Rotation of the hand wheel 30 acts to move the nut 27 back and forth in the pedestal 16, and the nut 27 acts through the plug 28 and the post 26 to move the bearing housing 25 on the pedestal 16 parallel to the angle guides 24.

The bearing housing 25 contains a fixed bear-

ing sleeve 31 and a movable bearing sleeve 32. Each of the bearing sleeves is provided at its extremities with conventional anti-friction shaft bearings, indicated at 33.

The movable bearing sleeve 32 is hingedly mounted on a hinge pin 34 extending through a side bracket plate 35 on the sleeve 32 and a corner bracket plate 36 in the bearing housing 25. The hinge pin 34 is positioned adjacent the rear extremity of the sleeve 32, and the forward extremity of the latter extends through a horizontally elongated guide opening 37 in the front wall of the housing 25.

A push block 38 is slidably mounted in a guide box 39 adjacent the forward extremity of the sleeve 32. The push block 38 can be forced against the sleeve 32 by means of an adjusting screw 40 threaded through a head 41 in the guide box 39.

A first roller shaft 42 is mounted in the bearings 33 of the fixed bearing sleeve 31 and projects forwardly therefrom to stationarily support an idler, disc rolling roller 43. A second roller shaft 44 is mounted in the bearings 33 of the movable sleeve 32 and projects forwardly therefrom to adjustably support a second power-driven, disc rolling roller 45. The projection of the shafts 42 and 44 are such that the two rollers 43 and 45 contact each other directly over the pivot bolt 21.

The shaft 44 also extends rearwardly from the sleeve 32, and upon this rearwardly extending portion thereof a driven sprocket 46 is mounted. The sprocket 46 is driven through the medium of a sprocket chain 47 from a drive sprocket 48 mounted on a sprocket shaft 49. The sprocket shaft 49 is rotatably mounted in suitable bearings 50 secured on the side wall of the sleeve 31. The sprockets 46 and 48 and the chain 47 are preferably enclosed in a safety housing 51 supported from the housing 25 on suitable brackets 52.

The shaft 49 terminates in any suitable coupling, such as a universal joint 53, to which a power shaft, indicated at 54, may be connected from any suitable source of power, such as the power takeoff of a conventional farm tractor. A suitable carrying handle 55 is mounted on and projects upwardly from the bearing housing 25 by means of which the device may be carried to the job.

In use, the device, with its supporting track, is carried to the implement having damaged discs. The track is laid on the ground adjacent the disc shaft of the implement in any convenient position, preferably parallel to the disc shaft, and the base plate 12 is moved along the track members 10 to position the rollers 43 and 45 opposite the edge of the damaged disc.

The power shaft 54 is connected to a source of power, to rotate the roller 45 against the disc and the disc against the idler roller 43. The hand wheel 30 is now rotated to force the bearing housing 25 toward the disc so that the rollers 43 and 45 will be forced onto the edge of the disc and toward the axis thereof while rotating, to iron out any dents, bends, or other irregularities in the discs.

It will be noted that the base plate 12 is free to move on the track members 10 and the pedestal 16 is free to rotate about its pivot bolt 21 to

follow the arcuate contour of the disc as the rolling progresses.

Should there be more than one damaged disc, the base plate 12 can be moved along its track to an operating position adjacent the second disc. The rolling pressure applied to the disc is adjusted by adjusting the screw 40 to vary the spacing of the rollers.

For straightening flat discs and the like, the pedestal 16 can be locked against sideward movement by means of the set screw 20 so that it will force the disc to a true plane condition.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A portable disc rolling device comprising: a base plate; a pedestal movably supported on said base plate; a vertical axis pivot member pivoting said pedestal on said base plate at one side of the former; a bearing housing supported on said pedestal; a horizontal bearing sleeve mounted in said housing; a movable, horizontal bearing sleeve mounted in said housing in substantially parallel relation to the sleeve; a roller shaft rotatably mounted in each sleeve and projecting forwardly therefrom; a roller mounted on the forwardly projecting extremity of each shaft, said rollers being adapted to contact the opposite sides of a disc, said housing being so constructed as to permit free entrance of the disc between said rollers; means for urging said rollers together; and means for rotating one of said rollers.

2. A portable disc rolling device as described in claim 1 having said bearing housing movably mounted on said pedestal; and means for moving said bearing housing horizontally on said pedestal in a direction parallel to said shafts.

3. A portable disc rolling device as described in claim 2 in which the point of contact between said rollers is directly over the pivot axis of said pedestal, and having means for locking said pedestal against movement about its pivot axis.

4. A portable disc rolling device as described in claim 3 having a pair of parallel track members positioned below said base plate; and runners on said base plate slidably engaging said track members.

LESLIE H. GOODELL.
